194,880

FLOWER BASKET HOLDER FOR CEMETERIES OR THE LIKE

John J. Hegarty, 237 N. Lehigh St., Tamaqua, Pa.

Filed Aug. 3, 1961, Ser. No. 66,184

Term of patent 14 years

(Cl. D35—3)

FIG. 1 is a front elevational view of a flower basket holder for cemeteries or the like showing my new design;

FIG. 2 is a top plan view thereof; and

FIG. 3 is an end elevational view thereof.

I claim:

The ornamental design of a flower basket holder for cemeteries or the like, substantially as shown.

References Cited in the file of this patent

UNITED STATES PATENTS

D. 170,315	Gerber	Sept. 1, 1953
2,261,326	Atkisson et al.	Nov. 4, 1941
2,794,496	Strand	June 4, 1957

OTHER REFERENCES

Giftwares, June 1956, page 30, lower left item.